CLAIM

The ornamental design for detergent tablet, as shown and described.

DESCRIPTION

The present invention is related to co-pending design application Ser. Nos. 29/097,257, 29/097,249, 29/097,254, 29/097,258, 29/097,255, which were filed herewith.

FIG. 1 is a perspective view of the detergent tablet showing my new design;

FIG. 2 is a front elevational view thereof, the back, right side, and left side elevational views, respectively, being identical thereto; and,

FIG. 3 is bottom plan view thereof.

1 Claim, 1 Drawing Sheet
